PACKET BOXING MACHINE AND METHOD

Rodney S. Pullen, Akron, Ohio

Application December 28, 1936, Serial No. 117,819

14 Claims. (Cl. 226—4)

The present invention relates to the stacking and boxing of packets, particularly of match packets, and while intended for any use to which it may be adapted is thought to be particularly desirable in the manufacture of match packets of book, of "Pullenlite" and of other types, for use cooperatively with the packeting conveyer to deliver, to stack and to box the packets from the packeting conveyer. It may provide for cutting away of the paper matches from their stub strips when the packets are for example of the "Pullenlite" type.

A purpose of the invention is to deliver packets simultaneously from a plurality of links of a match packeting conveyer, preferably from six links at a time, delivering the packets in their own planes usually head end foremost, subsequently stacking the packets with their opposite ends each alternately up and down, and at intervals delivering two rows of the stacked packets into a single box, or to arrange six rows of the stacked packets, three pairs of closely adjacent rows, at a boxing station for simultaneous delivery into three boxes at each delivery stroke of a boxing plunger.

A further purpose is to cut the stub strips from match packets alternatively after the packets have been delivered edgewise from a packeting conveyer or while the stub strips are still gripped by conveyer members.

A further purpose is to stack on end, with opposite ends each alternately up and down, packets that are being delivered in horizontal position, using the same plunger to forwardly progress the packets edgewise in their own plane, to cooperate in stacking them on end and step by step to move the stacked packets to a boxing station adjacent a boxing plunger.

A further purpose is to upset endwise packets which are progressing step by step, alternately one upon its forward end and the next upon its rearward end, and so on, in order to stack them with the opposite ends of successive packets each alternately directed one up and the next down.

As a part of the operation of upsetting packets which are being moved step by step, so as to stack them upon their forward and rearward edges alternately, a further purpose is to use friction between the guideway sides of the packets and the packets themselves to hold them in their partially upset position and to maintain them in upset position as they are moved further along their path of travel.

A further purpose is to provide alternate forms

and stacking mechanism for packets which are travelling step by step.

A further purpose is to synchronize the step-by-step operations of a match packeting conveyer, a packet delivery mechanism and stacking and boxing mechanisms.

A further purpose is to register two side-by-side stacks of packets under a box charging plunger for the simultaneous delivery of both stacks into the same box, each delivery stroke of the plunger charging a box for the length of the box with two rows of packets.

A further purpose is to provide a pair of packet guideways which support and deliver stacks of packets, with swinging floor sections at a box-charging station to hinge open in accommodating downward strokes of a box charging plunger, and to use the open floor sections to ensure proper registry of the box with the descending stacked packets. The sections are resiliently retracted with the upward return of the plunger.

A further purpose is to support a packet box in registry with two side-by-side stacks of packets in different packet delivery guideways in order that the two stacks of packets may be placed in the box coincidently.

Further purposes will appear in the specification and in the claims.

I have elected to illustrate my invention by one main form and a few minor modifications only among many forms available, selecting illustrations that are practical and effective in operation and which well show the principles involved.

Figure 1 is a schematic plan intended for a conventional illustration of the invention.

Figure 2 is a vertical section of a portion of Figure 1, taken upon the line 2—2 thereof, looking in the direction of the arrows, to illustrate a desirable form of packet stacking mechanism.

Figure 3 is a front elevation of a portion of Figure 1, additionally illustrating the desirable mechanism of Figure 2.

Figure 4 is a schematic elevation intended for a conventional illustration of the invention and showing a somewhat different stacking mechanism from that of Figure 2.

Figures 5 and 9 are hypothetical cam diagrams to illustrate different suitable timing relations of the mechanisms shown in Figures 4 and 3 respectively.

Figure 6 is a section of Figure 4 taken upon the lines 6—6 thereof, looking in the direction of the arrows.

Figures 6^a and 6^b are sections corresponding to Figure 6, but showing modifications.

Figure 7 is a left elevation of Figure 4, partly in section, but omitting part of the structure indicated schematically in Figure 4.

Figure 8 is a modified fragment of Figure 4.

Like numerals refer to like parts in all figures. Describing in illustration and not in limitation and referring to the drawings:—

Figure 1 is intended, in its broader aspects, for a conventional plan of any structure for carrying out the invention; along with which is shown some structure particularly intended for stacking "Pullenlite" packets 14 carried by their uncut match comb stubs 15 from the individual links 16 of the packeting conveyer 17.

The conveyer operates intermittently in timed relations with a conveyer delivery plunger 18 and feed frame 19. The conveyer 17 intermittently moves forward a distance of six links and at the end of each six-link forward movement brings six packet-carrying links to rest at their packet delivery positions.

This forward movement cannot take place except when the feed frame 19 is raised as is indicated in dot-and-dash lines in Figure 2.

In Figure 2 the packets of but one row show, but the same operations are applied to the packets of each of the six rows, here treated as formed together.

A selection of the six rows is not vital but is convenient. The 60-match comb forms six packets of convenient width and the division into six parts accommodates mechanism for cutting and spacing shown in my copending application. It is desirable that the number of rows be even so that the packets from two rows can be filled together into the same box.

The bodies of the packets which are intended to be handled by these respective links project laterally from the links and slide along the feed table 20. Their stub strips are engaged by the respective links and the movement of the respective links gives them their sliding motion along the feed table 20. They come to rest in what is here termed their delivery positions in which they underlap the raised frame 19.

The packeting conveyer may be of any suitable type provided it delivers the packets to a point at which they can be received and handled by the mechanism herein described. The one shown is well adapted to handle "Pullenlite" packets, because it allows the packet to project and supports it by uncut match comb stub material.

The feed frame successively lowers at the rear of the stroke, feeds forward, rises and retracts. While the feed frame remains raised the six forwardly projecting arms 21 of the plunger 18 make a forward stroke and at least partially retract. On their forward stroke they pass through the individual conveyer links sufficiently to push the still uncut stubs of the match comb sections within the packets free from their engagement within the conveyer and to place the packets in properly registered position below and within the space to be enclosed by the rearmost rectangular openings 22 of the feed frame.

After the plunger 18 retracts out of the way, the feed frame 19 descends to the full-line position of Figures 1 and 2, the rearward bar *a* of the feed frame falling back of the uncut comb stubs 23 of the packets now at stage A on the feed table 20.

The packets indicated at stages B, C, D, E and F respectively are packets which previously have passed through stage A and which have been advanced from stage A to stage B or from stage B

to stage C, or from stage C to stage D, or from stage D to stage E or from stage E to stage F, as the case may be, by operations of the feed frame, some being directly engaged by bars of the frame and others being shoved by packets 5 so engaged.

In the description for the present the operation in one row only will be described, the same thing taking place coincidentally in all six rows.

The feed frame 19 operates through a cycle 10 of successive feedings (to the left in Figure 2), upward movements to clear the packets, rearward retractions (to the right in Figure 2) and lowering in position to engage other packets. The cycle may therefore conveniently be divided into 15 downward and forward operating strokes and upward and rearward retraction strokes.

In Figure 2 the frame is shown after it has retracted rearwardly and has dropped to position so that the bar *a* lies back of the packet at stage 20 A and with the bar *b* in position back of the packet in stage B. There is a bar *c* which is a stiffening or holding member for the support of the packets during the cutting operation and the frame carries a bar *d* which engages and pushes 25 packets which have intermediately been turned up on end, alternate packets resting on the front and on the rear end of the packet later more fully disclosed.

The bars *a* and *b* are the only bars in the illustration which engage packets which are lying down flat, i. e., in horizontal position. This means merely that the operation can be performed without requiring more bars than this for the purpose indicated. Other bars of course 35 can be used.

The frame is shown in rear position in Figure 2. Between the stages A and B a cutter 24 is located which is shown in position to operate upon packets to cut off the stub ends at stage B while 40 the head ends of the packets are held against tilting by the bar *c*. The cutter is shown in the conventional form of a plain knife.

After the stub ends have been cut off and have been removed through the opening 25, the packets 45 in position B are moved by bar *b* to stage C at the same time that a new packet from stage A replaces the packet previously located at stage B.

The illustration in Figures 1 and 2 is schematic to the extent that it does not show any support 50 for the knife but a vertical slide 26 for the knife is shown in Figure 3.

The packets are guided at stage C by flange sides 27 and each packet as it progresses from stage C pushes the packet ahead of it into the 55 path of movement of plungers 28 and 29 which operate alternately, 28 as shown engaging the stem end of the packet to lift it about the head end of the package as a fulcrum, and plunger 29 engaging the head end of the packet to lift it 60 about the stem end of the packet as a fulcrum as shown respectively in dotted and in full lines in Figure 2. In either event the packet may be held by friction against the side walls in its tilted position until bar *d* carried by the feed frame 65 engages it and forces it from this stage D to the next stage E in which the packet has been straightened up to vertical position by pressure of the bar *D*.

As seen in Figure 2 the packet has been pushed 70 from the rear to stage D by the packet in stage C. Whether a separate bar of the feeding frame be used or not here is evidently optional. When the packet is up-ended from the front, the preceding packet (or the bottom of the bar *d* in 75

other figures) presses the bottom of the packet and helps to turn the packet fully to vertical position. Finally the upper part of bar *d* engages the upper part of the packet and pushes the packet against that one last previously up-ended.

Those packets which are tilted from the rear as by plunger *28* lose touch with the preceding flat packet and so are no longer shoved by it. However, the upper part of the bar *d* with the feed frame engages the upper parts of these packets directly and pushes them into engagement with the last packet up-ended. In either event the succeeding packets are pushed from stage to stage by the following packets. In this way a solid row of vertically placed packets is formed to the left in Figure 2 and is progressively fed to the left during the operation of the frame.

The up-ending is effective as described without further assistance but with some types of packet it may be desirable to additionally protect against the packets falling back from partially up-ended position such as, for example, the positions shown in Figure 2. In this case the walls of the guideway can be made narrow enough to give a frictional hold upon the packet throughout its progress. This is useful also in holding the packets after they have progressed beyond the up-ending stage and in order to prevent individual packets from falling out of the group as a row section of them is being forced down into the box during the boxing operation.

In the manner described successive row sections of packets are found in vertical position, the matches alternating with heads up and sticks up in successive row sections. Each section as it is completed is charged into the box as herein-after more fully described. Though individual charges filling the boxes are shown, the preferred construction charges each box from adjoining guideways with two parallel rows of packets.

The stage B has been set in order to cut the matches free from the stubs. This of course is unnecessary where the matches are not intended to be cut (as in the book type) or have already been cut.

The cutting stage has been included here because the "Pullenlite" match packets are most conveniently handled on the conveyer by their uncut stubs, leaving the operation of cutting to be performed either as the conveyer or—as at stage B—after the delivery from the conveyer. With book type matches, or where the cutting at stage B becomes unnecessary, the cutting can be omitted.

The feed frame moves up after each forward stroke and then while raised retracts to the position shown in dot-and-dash line, Figure 2, completing the cycle.

The packaging conveyer *17* may begin its next six-link advance as soon as the feed frame *19* moves out of the way of the new set of six packets. The new packets are discharged at their delivery positions in front of the plunger *18*.

Figure 3 is intended to illustrate suitable details of one desirable embodiment of the structure of Figure 2.

In Figure 3 the chain packaging conveyer *17*, not itself shown in the figure, is intended to travel along a conveyer guideway *31*, formed as part of the table *20*. Principal cam shafts are shown at *32* and *33*. These are rotated in the direction of the arrows, by any suitable means

in proper timed relations with the intermittent movements of the conveyer *17*, the shaft *32* to rotate twice for each single turn of the shaft *33*.

In the operation of the several plungers as described, the plunger *18* moves in horizontal reciprocation, the plunger for the knife *24* in vertical reciprocation, the plungers *28* and *29* both in vertical reciprocation and the feed frame *19* is horizontally reciprocated but at the ends of its stroke is lifted at one end and lowered at the other comprising a vertical reciprocation.

The reciprocation of the plunger *18*, the vertical reciprocation of knife *24* and both the horizontal and vertical movements of feed frame *19* take place one complete cycle to each rotation of shaft *32*. The reciprocations of the plungers *28* and *29* alternate so that one or other of them (but not both) reciprocates for each rotation of the shaft *32*. This is accomplished by operating both of them for each rotation of the shaft *33*, one during one half turn of the shaft and the other during the other half turn of the shaft.

In order to carry out the movements above and to provide balanced operating mechanism, the shaft *32* carries three sets of cams, respectively to operate the plunger *18*, to vertically position the feed frame *19* and to operate plunger *25* carrying the knives *24*; and the shaft *33* carries three sets of cams, respectively to horizontally reciprocate the feed frame *19*, to operate the forward upsetting plunger *28* and to operate the rearward upsetting plunger *29*.

Each set of cams includes two cams relatively spaced along the cam shaft. The two cams in each set unite to perform the same function. One cam only of each set of the six sets of cams is shown, the other of the pair, in each case, lying back of its mate and being identical with the one shown. The cams shown are in dot.

The plunger *18* is operated by spaced links *34*, of which one only is visible, intended to connect to a rocker bar *35*, pivoted at *36* to any suitable fixed member and carrying at its lower end a cam-engaging wheel *37*. The forward position of the rocker *35* is indicated in dot and dash.

The feed frame *19* has horizontal slide support at *38* in a vertical slide *39*, which slide *39* is positioned vertically by a cam *40* and a cam-engaging wheel *41*, carried by a downward extension from the slide *39*. The vertical slide *26* carrying the knives is vertically operated by cam *42* and a cam-engaging wheel *43*, respectively, the wheel being carried by a longitudinally adjustable link *44* connected at *45* with the slide *26* carrying the knives.

The feed frame is horizontally positioned by counterpart operating cams of one set located near opposite sides of the frame. Each cam is double thus operating once for each half turn. One double cam only shows in Figure 3. The connections with the feed frame include a link *46*, a rocker *47* pivoted at *48* and operated by engagement of the cam *49* with wheel *50*.

Likewise the front and rear upset plungers *28* and *29* carried by vertical slides *51* and *52* are each vertically operated by two counterpart sets of spaced cam and link mechanisms. One set only shows in Figure 3 and comprises laterally spaced rockers *53* and *54*, pivoted at *55*, rocker wheels *56* and *57* travelling in internal cams *58* and *59* and links *60* and *61* between the slides *51* and *52* and the rockers *53* and *54*, respectively. The members *53*, *56* and *60* in their full line positions are hidden by the members *54*, *57* and *61* and the numerals *53*, *56* and *60* have been there-

fore applied to the indicated dot-and-dash positions of the respective members.

The schematic elevations Figures 4 and 7, like Figure 1, are intended to be a conventional showing of any structure for carrying out the invention. As shown in Figure 4, the construction is suited for book type packets. By very slight modification (see Figure 7) it can be suited to handle "Pullenlite" packets.

- 10 In Figure 4 typical match book packets 14' are seen within links 16' of a match book packeting conveyer operating intermittently in proper timed relation with the conveyer delivery plunger 18' and feed frame 19' as already explained, generally, for Figure 1.

In that the packets of the match book type before their delivery from the conveyer do not project out of the conveyer links 16', these packets are initially out of the way of the feed frame, 20 which makes it permissible to have the horizontal forward strokes of the plunger 18' and of the feed frame 19' simultaneous, also to have their horizontal retraction strokes simultaneous and, as indicated, the horizontal movements of the 25 delivery plunger 18' and of the feed frame 19' are both operated from a cam shaft 62. They are both actuated by the same set (pair) of counterpart cams 63 at opposite sides of the machine through cam wheels 64 and rockers 65, 30 pivoted at 66. Each rocker 65 connects at the top by link 67 to the feed frame 19' and connects at the bottom by link 68 to a rocker 35', pivoted at 36' and operating the delivery plunger 18' by link 34'.

35 The feed frame 19' is shown as supported to slide horizontally at opposite sides in the vertical slides 71, that is through opposite counterpart supports, providing one support at each side of the frame, of which both are shown in Figure 40 7 but one only is shown in Figure 3.

The support is accomplished by providing the feed frame with pins 69 and 70 which extend inwardly, away from the observer in Figure 4, from the feed apron 19' into horizontal slots 72 in the upper parts of the vertical slides. They 45 are effectively parts of the feed frame. The feed frame is shown in its position farthest to the right in Figure 4.

One of the pins 69 at each side of the machine is extended outwardly toward the observer in Figure 4, to pass through a hole in the right-hand end (Figure 4) of link 67. This link is attached at its opposite end to the rocker arm 65 by a pin 73 with the purpose and effect that 50 movement of the rocker arm to left and right in Figure 4 will carry the feed frame with it to left and right, the heights of the feed frame during the movements being determined by the heights of the vertical slides 71.

60 The vertical slides 71 are guided suitably and are operated, to lift and to lower them, by cams 74 acting through cam wheels 75.

Packet upsetting or packet stacking means is shown as of a different character from that 65 shown in Figures 2 and 3 in that one plunger only is used in each of the six packet positions. The upender or stacker includes a plunger 76 having stacker arms 78 at its upper end spaced, one for each of the six packet rows which the 70 convenient subdivision of the match comb has made it desirable to treat at one time. The arms operate within slots 78'. The upender or stacker is supported on legs 79, rigidly connected at their lower ends to a rocker shaft 80.

75 The rocker shaft is journaled in a vertically

guided bearing 81. The rocker shaft is lifted and is allowed to lower by engagement with cams 82. The rocker shaft is held to its duty, i. e., is held against the cams by springs 83 which are compressed by the cam lift and which assist in the downward movement of the rocker shaft. They bear against the journal of the rocker shaft at one end and at the opposite ends are compressed against a stationary plate such as 84. Pins 85 above and 86 below, guided in stationary 10 structure 84 and 87, respectively, maintain the rocker shaft against movement circumferentially of the cam.

The stacker unit comprises the plate 77, arms 78, legs 79 and shaft 80. At the same time that 15 it is vertically operated by the cam 82 it is also subject to angular control about the shaft axis to shift from one upsetting or upending position, engaging let us say the rear end of the packet, to an opposite upsetting or upending position to engage the front of the packet, by laterally spaced longitudinally shiftable control bars 88.

The bars 88 as shown are threaded rods surrounded by springs 89 and 90 on opposite sides 25 of the upender or stacker, held in position by nuts 91 and 92. These springs are both under compression and permit some leeway in the position of the upender or stacker and at the same time provide adjustment by which the normal 30 position of the upender may be varied by altering the relative positions of the nuts 91 and 92.

The bar 88 is supported toward one end by engagement with the upender where the bar passes through it. It is supported at the other end in a link 93 pivoted to the bar at its lower end 94 and pivoted at the upper end at 95 to a fixed member 96.

The link 93 presents a nose 97 to a cam wheel 98. On alternate step-by-step advances of the cam wheel this nose rests in engagement with the crests 99 of the cam projections 100 and in the cam valleys 101, respectively. The cam is mounted upon a shaft 102. The shaft carries a ratchet wheel 103 which is operated step-by-step 40 by a pawl 104. The pawl is pivoted upon a rod 105 which passes through vertical slides 71. The pawl is lifted and lowered by the lifting and lowering of these slides with consequent correspondingly timed step-by-step actuations of the 50 ratchet wheel. Suitable means not shown is provided for preventing reverse movement of the ratchet wheel. The resetting of the upender, to get it ready for upending at the opposite ends of the packets at the next stroke, may take place 55 at any time between retraction from one stroke and the next upward stroke. The timing and mechanism shown cause resetting immediately after retraction of the upender.

With successive actuations by the pawl the cam 60 wheel presses the nose 97 out for one setting of the upender and next allows the nose to rest in a valley for the opposite setting. The noses 97 are kept pressed tightly against the cam wheels by springs 106 upon rods 88. The springs rest 65 at one end each against a fixed plate 107 and at the other end each are held compressed by nuts 108.

The angular shifting of the upender are "settings" of the upender and determine whether the 70 next lifting operation shall lift the upender beneath the front ends of the packets or beneath the rear ends of the packets.

As in the other forms the packets which are 75 upended are pushed to the left in Figure 4, either

by the continued movement of the following packet or by the operation of the bar *b* of the feed frame. In this particular illustration the bar *b* extends to the bottom of the guideway when in its downward position so that it is the lower portion *b'* which engages a packet upended at the front as in dotted lines in the illustration of Figure 4.

The feed frame bar *d* is used to advance the next following packet but the advance of this next following packet is not used here to push the lower end of the packet seen partly upended, notwithstanding that, in the absence of the portion *b'* of bar *b* it could be so used. The position of the bar *b* or of the upender, or both, would then be altered. When the packet is upended at the opposite end from that shown in dotted lines in Figure 4 the bar *b* of the feed frame will engage from the rear the upper end of the packet which is upended and will shove this packet forward. Before the feed frame moves far enough to engage the upper part of the upender the latter is withdrawn so that with further travel of the feed frame to the left in this figure the packet is pressed up against the next preceding packet and is caused to advance the next preceding packet and all before it, so that the packet now being applied takes the place of the last-applied packet shown in the figure.

In the structure of Figure 8 the stub ends may be delivered from the conveyer by a suitable delivery plunger generally like the plunger 18 of Figures 2 and 3 but located at an advanced position of the conveyer.

Referring again to the structures of Figures 1, 2, 4-7, the successive strokes of the feed frame and up-ending and stacking mechanism deliver the packets, one at a time, into each of the six guideways 111, up-ending the packets first at one end, then at the other and step-by-step progressing the packets, so arranged, in six rows along their guideways 111 to a discharge position under a plunger 112.

It is at present customary to pack fifty match packets to a box, each box to contain two rows of twenty-five each. As illustrated each delivery of the discharge plungers 113 is intended to take place after each twenty-five strokes of the feed frame and of cooperative mechanisms have progressed two row sections of twenty-five packets each until they lie under laterally spaced heads 114, 115, for the pair, there being also heads 116, 117 and 118, 119 for other pairs.

It is assumed that each delivery of the discharge member is to fill simultaneously three packet boxes 120, 121 and 122 with two rows of packets of twenty-five packets each.

The guideways 111 uniformly spaced from one another at their inlet ends at their discharge ends are brought near together and parallel in pairs, as in Figure 1, with the three pairs of guideways 111 registering at their discharge portions respectively above the boxes 120, 121 and 122 and under three corresponding pairs of plunger heads.

The boxes in the illustration are intended to be held resiliently in their receiving positions after an attendant has placed them, one at a time, to enclose at their ends thin guiding and supporting plates 123, 124. The plate 124 may be permanently stationary and the plate 123 movable and continuously resiliently pressing outward, the boxes being put in place by inwardly deflecting the plate 123 to bring the plates close enough together for both to enter the box interior.

When in place the boxes are held to position by the outward spring retraction of the plate 123 indicated as due to a compression spring 125 compressed between stationary structure and an offsetting bent portion 126 of the plate.

In their discharge positions, beneath the plunger heads, the guideways are shown as provided with floor plates 127 which act as doors. They are hinged at 128 outside of the line of the side guideway walls and below the guideways. For each box the doors of the two guideways swing

5 by the continued movement of the following packet or by the operation of the bar *b* of the feed frame. In this particular illustration the bar *b* extends to the bottom of the guideway when in its downward position so that it is the lower portion *b'* which engages a packet upended at the front as in dotted lines in the illustration of Figure 4.

The feed frame bar *d* is used to advance the next following packet but the advance of this next following packet is not used here to push the lower end of the packet seen partly upended, notwithstanding that, in the absence of the portion *b'* of bar *b* it could be so used. The position of the bar *b* or of the upender, or both, would then be altered. When the packet is upended at the opposite end from that shown in dotted lines in Figure 4 the bar *b* of the feed frame will engage from the rear the upper end of the packet which is upended and will shove this packet forward. Before the feed frame moves far enough to engage the upper part of the upender the latter is withdrawn so that with further travel of the feed frame to the left in this figure the packet is pressed up against the next preceding packet and is caused to advance the next preceding packet and all before it, so that the packet now being applied takes the place of the last-applied packet shown in the figure.

30 One advantage of the type of upsetter indicated in Figure 4 is that lateral play is permitted at the top upender where the arms of the upender pass through the slots in the floor of the guideway. These slots are made somewhat longer than are necessary for the upender to shift from one position to the other for its intended upending in order to accommodate this additional movement.

35 The provision for additional movement does not alter the correct positioning of the upender for each upending stroke but does permit the upender to be carried to the left in Figure 4 by engagement of the packet or of the bale *b* with the packet during the travel of the feed frame. This play for lateral movement of the upender to the left is permitted by compression of the 40 spring at the left lying between the upender and the nut 91.

45 There would be corresponding freedom for additional movement of the upender to the right in the figure but this is not needed.

50 If separate support of the packets be given at opposite sides, the packets will stay in partly upended position while the upender is withdrawn and until the feed frame engages the packets to push them into position in the row section. Otherwise the upender would be held up supporting the partly upended packet, at whichever end the upending has taken place, until the packet has been engaged by the feed frame and has been lifted by the feed frame to a position where the feed frame will control it and will prevent it from falling back to flat position or from falling back far enough to give difficulty in wedging it into vertical position by the feed frame pressure.

55 During each forward advance of the delivery plunger 18' six books are swept out of the links of the packeting conveyer, one from each of the links, to positions A upon the feed table 20'. At the same time that the plunger 18' advances the feed frame moves forward in lowered position, its rear transverse bar *a* advancing the six books which have previously been at stage A to a flat position at stage B. This is the upending position. During the same forward stroke that delivers packets from stage A to stage B the trans-

downwardly and away from each other so that the two doors engage the inner side walls respectively nearest their hinges. The doors are bent or offset at 129 but those portions of the doors 130 which normally form the floors of the guideways are straight and approximately perpendicular to the side walls of the guideways under any closed position. Because of the bend or offset these floor portions of the doors in open position will be approximately parallel with and closely against the respective inner side walls of their boxes and are helpful not only in guiding the packets into the boxes but in maintaining the full width of the box opening during the filling operation. In this particular they perform part of the same function at the sides of the box that the end parts perform at the ends of the boxes. The spring character of the end plates gives them a supporting function also in that they hold the box up and that the box is ultimately removed from them by pressure through the packets.

As the plunger heads are moved down by any suitable means—and of course in proper time relation with the operations of the feed frame and its cooperating mechanisms—each head first engages the packets under it and then in pressing the packets down each forces its floor door open. The two rows of packets for any box enter the box between the opened floor doors which when open present their lower edges inside the box along opposite walls thereof. With continuing downward movement of the plunger heads each box remains stationary until the packets engage the bottom of the box, after which the box travels down ahead of the plungers until it drops off from the supporting end plates to any suitable conveyer not shown.

When the plunger heads retract upwardly the floor doors are closed automatically by any suitable springs shown diagrammatically at 131.

In Figures 4 and 5, the plunger heads, intended to operate in any suitable way after the right number of stacked packets has been positioned beneath them, are indicated as operated by a bell crank 132, pivotally supported at 133. One arm 134 forks over projecting pins 135 of the plunger. The bell crank is shown diagrammatically as spring retracted upwardly by spring 136. The lower end of the other arm is provided with a hook link 137 adapted to hook back of a pin 138 in the upper end of the rocker 65 at the end of an advanced rocker stroke.

The hook link 137 normally is prevented from hooking to the pin 138 by a vertical slide pin 139 supported by a cam 140. The cam is mounted rigid with a ratchet wheel 141, both upon shaft 142. A pawl 143 carried by the rocker 65 advances the ratchet wheel and thus advances the cam wheel 140 one step during each advance stroke of the rocker 65. After the desired number of steps (herein assumed to be twenty-five in that twenty-five is at present a usual and convenient number of packets in each box row) the cam wheel advance brings a notch 144 into registration with the pin, the pin permitting the hook link 137 to hook back of the pin 138. The normal retraction stroke of the rocker 65 then moves the plunger unit downwardly to discharge the stacked packets which lie under the respective plunger heads of this unit.

Desirably the plunger unit should retract before the next advance of the feed frame, for which reason the bell crank 132 has been shown with retraction by spring 136 to be operative after or

at the completion of the retraction stroke of the rocker 65. At this time it lifts the hook 137 from the pin 138, as by a suitable wedge 145 supported by the table and in position to engage the hook and lift it at the end of its retraction stroke.

In Figure 6a one pair of guideways only is shown in a modification. The section is across the box as in Figure 6 and the structure is of the same general character as in connection with one of the pairs of guideways. The end plate support for the boxes can be used as in Figure 6 but the doors of Figure 6 are wholly absent. In their place provision is made by friction on the sides of the packets for retardation against downward movement of the packets under plunger operation. The packets are advanced in a straight line by proper action of the feed frame. Since its entire operation is in a horizontal plane and the packets are not free to drop as they pass along the guideways, there will be but little drop of these packets and they will reach discharge position with the packets substantially fully raised. The pressure on the packets will discharge them through the open bottom. In this case the pull of the end plates lengthwise of the box against the ends of the box is relied upon to hold the sides of the box fully extended.

Since the friction of the normal guideway sides can be relied upon to give good results in view of the compressibility of the packets, special friction material will ordinarily not be required; however, felt linings of one side of each guideway are shown at 146 to provide comparative compression within the walls and quite measurably to increase the friction which retards any casual or accidental movement of the packets.

In Figure 6b the box 120' is shown having width for one row of packets only. The end plates are here again used to hold the box and to guide at the ends. However, in this case, the doors are split at the center at 147 and each half door is shaped, hinged and spring retracted in the manner indicated in Figure 6. In this illustration each half door performs the function of the full door in Figure 6 in that it may press against the side box walls and affords a guide for the packets while protecting against side box wall intrusion. The half doors are so short in width as to offer little need for bending the doors adjacent to the hinges.

In Figures 5 and 9 hypothetical timing diagrams have been added merely to illustrate more clearly the timing relations of the principal parts of the structure of Figures 4 and 3 respectively. These diagrams carry notations which are thought to make their application apparent and further description is therefore considered unnecessary.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:

1. The method of forming on a table rows of match packets for boxing, which consists in delivering the match packets for each row successively in flat position on the table, in advancing them on the table step by step in flat position, in

tilting the alternate packets reversely between successive step-by-step advances at one of their step positions, lifting the front end of the first while it is at the said one position and the rear end of the second while it is at the said position and so on, in continuing the upending movement and the advancing movement of the packets on the table by forwardly directed pressure upon the rearward ends of the tilted packets and in forcing the upended packet against the packets which have been upended before it to form on the table a progressive advancing row of upended packets.

2. The method of forming rows of match packets for boxing, which consists in delivering the match packets successively in flat position, in advancing them in flat position, in tilting them alternately successively on front and rear edges by raising the rear and front edges while frictionally engaging the sides to hold them in tilted position, in progressively increasing the tilting movement to upending by forwardly directed pressure upon the rearward ends of the packets while continuing to frictionally engage the edges of the packets and in progressively pushing the packets as they are upended into engagement with the packets last previously upended to form an increasing row of upended packets.

3. In mechanism for feeding and stacking match packets, a conveyer adapted to carry a succession of packets, plunger means for ejecting the packets in succession, a table upon which the packets are delivered, means for advancing the packets on the table, and plunger means operating alternately at different ends of the successive packets to lift one end of each packet and thus reversely to tilt successive packets, the said advancing means being movable successively down, forward, up and rearward and including means operative on the forward movements for engaging the successive partly tilted packets and upending them.

4. In feeding and stacking mechanism for match packets, a table upon which match packets are placed in succession, feeding mechanism and means for moving it downwardly, forwardly, upwardly and rearwardly by which the packets are engaged and advanced flat on the forward movement to upending position and plunger means operating on the packets successively and at opposite ends of the successive packets to lift the front end of one packet and the rear end of the next packet and so on, the said feeding mechanism including means for engaging the tilted packets successively on each forward movement, upending the tilted packets, one at a time, and pressing it into engagement with the last previously upended packet.

5. In feeding and stacking mechanism for match packets, a table upon which match packets are placed in succession, feeding mechanism and means for moving it downwardly, forwardly, upwardly and rearwardly by which the packets are engaged and advanced flat on the forward movement to upending position and plunger means operating on the packets successively at opposite ends of the successive packets to lift the front end of one packet and rear end of the next packet and so on, the rearward edges of alternate packets being pressed forward by the following packets and the said feeding mechanism including means for engaging the tilted packets to upend them and force them against previously upended packets.

6. In mechanism for feeding match packets,

a table, a feed frame having a rear feeding bar, means for giving the feed frame vertical and horizontal movements whereby the bar is adapted to advance flat packets on the table, vertically reciprocable plunger means operating alternately at the front and rear of successive packets to lift the front of one packet and the rear of the next packet and so on, and a bar carried by the feed frame adapted to engage the tilted packets and upend the packets, alternate packets being shoved by preceding packets to assist in the upending of the packets.

7. In mechanism for feeding match packets, a table, a feed frame having a rear feeding bar, means for giving the feed frame vertical and horizontal movements whereby the bar is adapted to advance flat packets on the table, vertically reciprocable plunger means operating alternately at the front and rear of the packets to lift the front of one packet and the rear of the next packet and so on, the walls at opposite sides of the packets engaging the side edges of the packets and causing them to be retained in position to which they have been lifted.

8. In upending mechanism for match packets, walls forming a guideway for the packets in which the packets are delivered flat and tilting means for the packets comprising a pair of upwardly and downwardly movable plungers located near the front and rear ends of flat packets in one position in the guideway, cam means for lifting the two plungers successively, a vertically and horizontally movable feed frame, cam means for operating the feed frame and a bar on the front of the feed frame adapted to engage packets in tilted position and upend them.

9. In mechanism for feeding and upending match packets, walls forming a guideway, horizontal feeding mechanism for advancing the packets in the guideway, cam means for operating the feeding mechanism, a shaft operating the cam means, a second shaft having half the speed of the first shaft, cams on the second shaft operating once for each rotation of the second shaft, a pair of plungers operated respectively by the different cams and operating alternately once for each rotation of the second shaft and adapted to engage respectively the front and rear ends of a packet as delivered by the feed frame and means upon the front of the feed frame for assisting the plungers in upending successive packets.

10. In mechanism for feeding and boxing match packets, a conveyer, means for ejecting packets from the conveyer, an upwardly and downwardly movable plunger, cam means for lifting and lowering the plunger, cam means for swinging the plunger to engage a packet alternately beneath the front end and beneath the rear end of the packet, resilient connections whereby the plunger is free to shift laterally in either position into its place, a feed frame adapted to deliver packets in position for the tilting by the plunger and adapted to shift the packets from tilted to upended positions whereby a row of upended packets is formed, plunger means for pushing a predetermined number of upended packets down into a box and cam means for operating the plunger at intervals corresponding with the formation of a pack to be boxed.

11. In feeding and stacking mechanism for match packets, a table upon which match packets are placed in succession, feeding mechanism and means for moving it downwardly, forwardly, upwardly and rearwardly, by which the packets

75

- are engaged and advanced flat on the forward movement to upending position, plunger means operating on the packets successively at opposite ends of the successive packets to lift the front end of one packet and the rear end of the next packet and so on, and friction means engaging the sides of the packet being tilted for momentarily retaining the packets successively in tilting position when the plunger means is withdrawn, the rearward edges of alternate packets being pressed forward by the following packets and the said feeding mechanism including means for engaging the tilted packets to upend them and force them against previously upended packets.
12. In mechanism for boxing match packets, walls forming a guideway, means for delivering packets flat in the guideway, a plunger and connections adapted to lift and lower to engage ends of the packets to tilt the packets successively, setting means for the plunger to cause it to engage one end of one packet or the other end of the next packet alternately and feeding means for engaging the packets and completing the upending of the packets.
13. In mechanism for boxing match packets, walls forming a guideway for packets of width slightly less than the width of the packets so that the packets will stay in any position to which they have been forced, the guideway having an open bottom near one end, means for delivering the packets successively flat in the lower part of the guideway, plunger mechanism for lifting one end each, alternate ends, of successive packets to cant the packets, a feed bar engaging the packets to turn them from canted position to upended position and to push the packets one against another into position in the guideway over the open bottom and plunger means for pushing the packets down through the open bottom.
14. In a machine for boxing match packets, a pair of guideways, means for intermittently delivering packets flat upon the guideways, means for intermittently advancing the packets along the guideways, means for reversely tilting successive packets operative between intermittent advances of the packets so that the tilted packets in the next packet advance automatically stack broadwise of their guideways alternately end for end, each packet broadwise of its guideway intermittently advanced along the guideway by the packets behind it to a position for its downward delivery from the guideway, the guideways beyond the stacking position being close together and having a downward delivery opening along a portion each thereof, movable doors across the openings, a support for a packet box adapted to present the box open beneath the openings and the doors as they open downwardly overlapping the opposite sides of the box, and means for pushing match packets concurrently from both guideways down into the box.

RODNEY S. PULLEN.
